A. STRONER.
TOOL FOR APPLYING SACK TIES.
APPLICATION FILED JUNE 21, 1919.

1,322,971.

Patented Nov. 25, 1919.

UNITED STATES PATENT OFFICE.

ANTHONY STRONER, OF FLORENCE, COLORADO.

TOOL FOR APPLYING SACK-TIES.

1,322,971.

Specification of Letters Patent. Patented Nov. 25, 1919.

Application filed June 21, 1919. Serial No. 305,797.

To all whom it may concern:

Be it known that I, ANTHONY STRONER, a citizen of the United States, residing at Florence, in the county of Fremont and State of Colorado, have invented certain new and useful Improvements in Tools for Applying Sack-Ties, of which the following is a specification, reference being had to the accompanying drawings.

10 This invention relates to an improved tool for applying a sack tie.

One of the objects of the invention is to provide a tool having a pair of jaws, the terminals of which being provided with 15 means to receive the two ends of the wire tie, whereby when the tool is turned (by any suitable power), the end portions of the tie are twisted, thereby forming the tie or knot for the sack.

20 The invention further aims to provide detachable means on the terminals of the jaws, for the reception of the end portions of the tie.

The invention further aims to provide a 25 pair of jaws, which are held normally sprung apart through the medium of improved tensioned means, in order to hold the terminals of the jaws in position, to receive the end portions of the wire tie, so that as 30 the end portions of the tie are twisted together to form the knot, the jaws are drawn together against the action of the tensioning means, in order to effectively form the tie.

The invention further aims to provide an 35 improved head for the jaws, said head having abutment means for limiting the jaws inwardly toward each other slightly spaced apart, and limiting the jaws spaced a substantial distance apart, particularly at their 40 terminals, which have the means for receiving the tie, said tensioning means acting to hold the jaws spread apart.

The invention further aims to provide a 45 head for the jaws having means to receive a spindle, which may be operated in any suitable manner (not shown), for holding the head in position, so that the jaws may receive the tie, it being the aim to rotate the spindle several revolutions, preferably three 50 times, though not necessarily, for it is obvious that the spindle may be rotated as many times as desired.

The invention further aims to provide 55 detachable means on the terminals of the jaws for receiving the tie, each detachable means comprising a plate for the reception of the

securing means to secure it to the tie and a lateral hook, which is engaged by the end portion of the tie, so that one end portion of the tie may be twisted into engagement with 60 the other end portion of the tie.

While the design and construction at present illustrated and set forth is deemed preferable, it is obvious that as a result of a reduction of the invention to a more practical 65 form for commercial purposes, the invention may be susceptible to changes, and the right to these changes is claimed, provided they are comprehended within the scope of what is claimed.

70 The invention comprises further features and combination of parts, as will be hereinafter set forth, shown in the drawings and claimed.

75 In the drawings:

Figure 1 is a perspective view of a tying device or tool, constructed in accordance with the invention and showing the tying jaws thereof spread apart for their full distance, and showing the tie in position in the 80 act of engaging about the neck of the sack.

Fig. 2 is a longitudinal sectional view on line 2—2 of Fig. 1, showing the tying jaws thereof spread apart for their full distance in full lines, and drawn together as the tie 85 is made in dotted lines, thereby illustrating how the tie is formed about the sack (not shown).

Fig. 3 is a transverse sectional view on line 3—3 of Fig. 1.

90 Fig. 4 is an enlarged detail perspective view of one of the detachable plates having a tie engaging hook and showing the plate in the position ready to be applied to the terminal of one of the jaws.

95 Referring more especially to the drawings, 1 designates a tool head as a whole, which comprises a body having a threaded part 2 at one end, for the reception of a spindle (not shown), which spindle may be operated by any suitable power (not shown). The body of the head at the end opposite the threaded bore is provided with opposing plates or parts 3, between which the tying jaws 4 are pivoted, as shown at 5. Extending transversely of the opposing plates or parts of the head is a pin 6, which extends across the space between the two opposing parts or plates. The short arms of the jaws 4 have their adjacent faces near their terminals provided with bevels 7, and adjoining these bevels, the short arms of the jaws are 100 105 110

provided with notches 8, to engage the transverse pin 6, so as to limit the outward spread of the longer arms of the jaws. This transverse pin not only limits the longer arms of the jaws in their sprung apart positions, but also limits the beveled faces 7, so that they are slightly spaced apart, when the longer arms are sprung apart, as shown in full lines in Fig. 2. Two of the opposite outer faces 10 of the body of the head are provided with recesses 9, in which plates 10 are secured by means of the screws 11. The inner faces of these plates are designed to be engaged by the outer faces of the short arms of the tying jaws, in order to limit the tying jaws slightly spaced apart, when moved to positions adjacent each other. Also secured by the screws 11 on the outer faces of the plates 10 are additional plates 12 provided with 20 outwardly turned apertured ears 13, to which coil springs 14 are connected, as shown. Secured by screws 15 to the outer faces of the longer arms of the jaws are plates 16, which also have outwardly turned apertured ears 17, to which the coil spring 14 are connected. It will be seen that these coil springs hold the longer arms of the jaws spread apart, with the notches 8 of the shorter arms in contact with the transverse 30 pin 6. The outer faces of the longer arms of the jaws adjacent their terminals are provided with recesses 18, in which the plates 19 are secured by means of the screws 20. The terminals of the plates 19 are provided 35 with hooks 21, which are disposed laterally relatively to the faces of the longer arms of the jaws, that is the faces at right angles to the faces having the recesses 18. The hooks are preferably of the design shown, though 40 not necessarily, for it is obvious that they may be any other suitable shape. The tie for the sack comprises a single length of wire 22 having its opposite ends provided with knots or twists 22^a. This tie, consisting of the wire, is placed in position, as shown in Fig. 1, with the end parts of the wire in engagement with the hooks, the knots or twists preventing the end portions of the wire from pulling through the hooks. 50 It will be noted that the sack is positioned as shown between the end parts of the wire tie

and the jaws. The spindle (not shown), but which carries the head of the tool, is then rotated sufficiently, approximately three revolutions, more or less, thereby twisting the 55 end portions of the wire tie together. As the end portions of the wire ties are twisted together, the jaws are drawn toward each other against the action of the coil springs, until the jaws assume the positions as shown 60 in dotted lines in Fig. 2, in which case the end portions of the tie have been twisted together, forming a knot with the wire engaging about the open neck portion of the sack, 65 preferably a cement sack, though not necessarily, to hold the sack securely tied.

The invention having been set forth, what is claimed as new and useful is:

In a tying tool, the combination with a body member having a threaded bore to be 70 engaged by a revolvable element to correspondingly rotate the body, said body having a bifurcation and provided with opposing plates caused to be formed by the bifurcation, the opposite edges of the body being 75 recessed at right angles to the plates, a pair of pins engaging through the plates adjacent their corresponding corners, a pair of members pivotally mounted upon said pins in opposed relations and having long 80 and short arms, the long arms constituting jaws proper having hooks to be engaged by a tie, the end portions of the short arms being beveled correspondingly, said bevels adapted to oppose each other when the jaws 85 are spread apart, an additional pin mounted in said plates engaged between the bevels to limit the jaws in spread apart relations, plates secured in said recesses and overlying the bifurcation and constituting abutments 90 for the shorter arms, securing means for said last mentioned plates, and spring means connecting said longer arms and the securing means to hold the jaws in normally 95 spread apart positions.

In testimony whereof I hereunto affix my signature in the presence of two witnesses.

ANTHONY STRONER.
